CHARGING DEVICE FOR INTERNAL COMBUSTION ENGINES

Ernest Frederick Ryder Townshend,
Waterlooville, EnglandApplication October 1, 1946, Serial No. 700,415
In Great Britain October 5, 1945

14 Claims. (Cl. 123—180)

1.

This invention relates to internal combustion engines, in particular to those which operate wholly, partially or occasionally upon gas fuel; and while the application hereinafter to be described is to a railway locomotive engine, it will be understood that the invention is capable of application in other fields. Furthermore, while this invention is particularly designed for use in conjunction with a form of the gas injection valve and ignition apparatus described in British patent specification No. 527,612 or a modification thereof, it will be understood that it may also be applied in conjunction with other suitable fuel injection and ignition apparatus.

One object of the present invention is to reproduce in an internal combustion engine an approximation to or an improvement upon the torque-speed characteristics of the conventional steam locomotive, to enable the internal combustion engine to be directly coupled to the driving wheels of a locomotive and thus to avoid the complications, weight, cost and losses inherent in any form of indirect drive.

The main requirements are that the internal combustion engine should begin to function satisfactorily as such while still at rest and that the torque exerted while at rest and up to a moderate speed should be a maximum. Thereafter the torque may diminish as speed increases.

The invention, therefore, consists broadly in the provision of means to secure high torque at starting and while accelerating, during which times a store of energy, in the form of compressed air, is drawn upon in an economical manner. This may take place in two phases, which will be referred to as starting and boosting. Means may also be provided to maintain a high torque at low and medium speeds when it is not permissible further to exhaust the stores of compressed air.

Thus according to one feature of the present invention an internal combustion engine includes means, capable of operating when the engine is stationary, for introducing a charge of compressed air into the cylinder, means for thereafter introducing fuel into the said charge of air in the cylinder, and means for igniting the fuel as it enters the cylinder. The admission of air may be controlled by a metering device which automatically cuts off the supply when a pre-

2.

determined quantity has passed, irrespective of the engine speed. The metering device preferably controls the admission of fuel as well as the admission of starting air, and may for example comprise an air-driven motor having reducing valves both on its inlet and delivery sides and an engine air admission valve arranged to be closed by a predetermined rotation of the motor. Conveniently the metering device operates through servo-mechanism, for example contacts and a solenoid.

It is desirable during this phase to provide means for controlling the combustion pressure. Thus a further feature of the invention is the provision of means for automatically controlling the rate of admission of fuel in accordance with the pressure in the engine cylinder so as to prevent the latter rising above a predetermined figure. Such means may comprise an auxiliary cylinder containing a piston subject to engine cylinder pressure tending to move it away from a stop against a resilient force, the fuel injection valve being so controlled by the piston that its opening is reduced if the piston is displaced from its stop.

When the engine has in this way been set in motion, a more economical cycle, which may be termed boosting, is adopted. Thus a further feature of the invention is the provision of means for introducing precompressed air into the cylinder late in the compression stroke and thereafter injecting fuel to give a high mean pressure without excessive maximum pressure or temperature. The starting air valve may be used for admitting this delayed supercharge. The air for this boost may be supplied from a high-pressure reservoir through a reducing valve and an equalising chamber, so that if at low speeds the cylinder pressure exceeds the pressure setting of the reducing valve while the starting air valve is open, air can be returned from the cylinder to the equalising chamber to prevent overcharging of the cylinder.

During normal running, when it is clearly impracticable to continue to draw upon supplies of compressed air, the supercharge, admitted at the beginning of the compression stroke as is usual, is supplied from an exhaust-driven turbo-blower, while scavenge air is supplied by an engine-driven scavenge air pump.

At higher speeds an excess of power and of supercharging air may become available and part of the scavenging pump output may then be used in conjunction with a second stage air compressor to pump up the air reservoirs, the excess supercharging air being directed to the scavenging manifold. But as a general rule the air reservoirs would be pumped up at such times as it is required to retard the engine and train, the scavenging pump and the second stage air compressor then functioning as a regenerative brake. 10

It may here be noted that in the aforesaid starting, boosting and heavy supercharging cycles the temperature of the cylinder contents immediately before the promotion of ignition is much below that at the corresponding point in compression-ignition oil engines. 15

Further features of the invention will be apparent from the description given hereafter.

The invention may be carried into effect in various ways but one arrangement will be described by way of example with reference to the accompanying drawings in which

Figure 1 is a schematic diagram showing the system of a two stroke gaseous fuel internal combustion engine suitable for direct coupling to the wheels of a locomotive,

Figures 2 to 5 are typical theoretical indicator diagrams illustrating a starting cycle (Figure 2), a boosting cycle (Figure 3), a heavy supercharging cycle (Figure 4) and, for comparison, an un-supercharged cycle, (Figure 5).

Figure 6 is a diagram showing means for controlling the latest permissible cut off in accordance with supercharge and speed,

Figure 7 is a diagram showing the electrical circuit and timing system of the embodiment of Figure 1.

Figure 8 is an enlarged view of part of the embodiment of Figure 1 showing the hydraulic and pneumatic connections, with the electrical circuit removed for clarity, and,

Figure 9 is a greatly enlarged view, partly in section, showing the arrangement of components in and adjacent to the cylinder head of the embodiment of Figure 1.

In Figures 2 to 5 of the drawings, the following abbreviations are used for the expressions here indicated:

P represents pressure.

V represents volume.

T°F. Abs. represents temperature in degrees absolute on the Fahrenheit scale.

T. C. A. represents temperature of charging air.

N represents compression or expansion index.

Vc represents clearance volume.

I. M. I. P. represents ideal mean indicated pressure.

A. M. I. P. represents actual mean indicated pressure.

B. M. E. P. represents brake mean effective pressure.

The expression used in Figure 2 "charge 4/1+454 B. t. u./lb." represents a supercharge of 400% added to the normal charge to which total air charge 454 British thermal units of heat are added per pound. Similar expressions are used in Figures 3, 4 and 5.

Each of the Figures 2 to 5 bears reference numbers 1, 2, 3, 4, 5 and 6 at various points on the cycle shown in the figures, and underneath each is a table giving the temperatures reached at these points in the cycle.

It will be observed that whereas in Figures 2,

3 and 5 the index N is the same for expansion and compression, in Figure 4 the compression index between 3 and 4 is given as 1.2, whereas the expansion index between 6 and 7 is 1.4.

Figure 5 enables a comparison to be made between the performance of the engine described below when operating on any of the cycles of Figures 2 to 4, and the performance of an ordinary supercharged internal combustion engine operating at maximum power between the same limits of temperature and pressure.

In practice the engine might comprise a horizontal two-stroke cycle engine of several cylinders (of which one only is indicated in the drawings), the pistons being connected to cranks on the driving wheels and axles by means of connecting rods. Connected to this engine and forming a part of it, for example, horizontally opposed to it, is a crank-driven dual purpose air pump, which functions at one time as a scavenging pump and at another time as the first stage of a starting and boosting air compressor. The second stage of the latter is preferably gear-driven from one of the axles. Above this engine may be arranged several air reservoirs, to contain air at a maximum pressure of some 450 lbs. per square inch, and the exhaust gas-driven turbo-blowers, auxiliaries and control gear. In the tender of the locomotive is carried the fuel, which may consist of coal gas or other inflammable gas, such as methane, either contained in metal cylinders under high pressure, or in the liquid state in a suitably insulated tank, or otherwise. If the fuel is carried in the liquid state provision must be made to evaporate it under pressure, as by means of a small exhaust gas single-tube boiler.

The conditions of use of such an engine demand widely different characteristics depending on the particular circumstances, and the engine shown is arranged to function in accordance with three different cycles, referred to herein as starting, boosting, and normal running, as well as a variation of the last of these. Briefly, during the starting cycle a metering device measures out a suitable charge of compressed air which is admitted to the cylinder and this is immediately followed by a charge of compressed gaseous fuel which is injected into the charge of air in the cylinder, and ignited as it enters, by means of an injection and ignition device similar to that described in British patent specification No. 527,612.

The starting cycle is capable of functioning while the engine is at rest and serves to set it in motion and give it some initial acceleration. When the engine has gained some speed the arrangement is changed over to the boosting cycle in which a charge of cold compressed air from a reservoir is admitted to the cylinder late in the compression stroke and the fuel thereafter injected into it and ignited by the same fuel valve as before. With further increase of speed a further change is made to the normal running cycle in which the supercharge is introduced at the beginning of the compression stroke.

In the particular arrangement shown in the drawings, a two-stroke engine cylinder 60 is equipped with a fuel injection-ignition valve 61, as described in the before-mentioned specification, excepting that the hydraulic relief valve (numbered 15 in that specification) is dispensed with. The fuel injection valve is described in detail in the prior specification, but briefly as indicated diagrammatically in the accompanying drawings, it comprises a needle valve which can

be opened by the admission of hydraulic pressure to a chamber 13 (using the same reference numerals as in the prior specification) through passages 14. Provision is made for igniting the fuel by electric sparks as it is injected into the cylinder. A sleeve 7 is arranged to control the amount of opening of the valve and rotation of the sleeve 7 varies the extent to which the valve can open.

The hydraulic chamber 13 in the valve 61 communicates directly through passages 14 and 16 with a hydraulic distribution valve 62 in connection through pipes 186 and 187 with respectively a hydraulic accumulator 63 and a tank 64. The distribution valve 62 is of a balanced, piston type. It is arranged to be operated by a solenoid 65 acting in opposition to a spring 180.

In order to secure the proper timing of the injection and ignition of fuel, electric current is supplied appropriately to the solenoid 65, through any suitable timed switchgear such as a cam-switch or rotating contact segment. The use of a pair of rotating contact segments in series makes it possible readily to vary both the beginning and end and the duration of injection. As shown the switchgear 66 consists of a pair of brushes 67 and 70 bearing respectively on a slip-ring 68 and a segment 69 attached to it. This switch is connected in series with another similar assembly 160 comprising brushes 71 and 72. The sliprings and their associated segments are suitably insulated and mounted on a cam shaft 89, by which they are revolved at engine speed. Segment brushes 70 and 72 are arranged to have a measure of angular adjustment about the cam-shaft, whereby the timing of admission and cut-off can be varied, and for the purpose of reversal.

This electrical circuit also has in it a selector switch 73 the position of which determines whether the starting, boosting or normal running cycle is selected. When starting this switch is so placed as to introduce into the circuit a further automatic switch 74 controlled by an air metering device presently to be described.

To prevent the pressure in the engine cylinder from becoming excessive during starting the rate at which gas is injected by the valve 61 is automatically controlled by a pressure regulator. This consists of a piston 75, subject on one side to pressure from the engine cylinder and on the other side to an opposing pressure applied in any suitable manner. The piston 75 is connected to the sleeve 7 which limits the lift of the valve 61 in such a manner that when the piston 75 moves outwards the sleeve 7 moves inwards, thus reducing the lift of the valve and therefore, the rate of injection of gas. In practice the piston 75 may carry piston rings and may terminate in a mitre head which normally mates with a complementary seat in the cylinder head as shown. The external load may conveniently be applied by means of air pressure and spring pressure, a combination which can be arranged to give to the regulator the requisite degree of sensitivity without introducing excessive bulk. As shown, the air pressure is derived from an air vessel 77 through a pipe 181 and applied to the piston 75 through a larger piston 76 upon which a spring 78 also bears.

The connection between the piston 76 and the sleeve 7 may be made in several ways, for example it may be made hydraulically as shown in the drawing. Here the sleeve 7 is split, the lower part forming a floating, annular piston 82 which is actuated by hydraulic pressure from a cylinder

83 containing a piston 84 actuated by the piston 76. The tank 64 is connected through pipes 182 and 183 to the cylinder 83 (as shown best in Figs. 8 and 9) and through pipes 182 and 184 and a non-return valve 185 to the split sleeve 7.

For the purpose of admitting air both when starting and when boosting the engine cylinder 60 is provided with a starting and boosting air valve 86. This is operated by hydraulic pressure from the hydraulic accumulator 63, through the medium of a solenoid-operated distribution valve 87, which, when the selector switch 73 is set to "start" is controlled jointly by a single electrical cam-switch 88, similar to the cam-switch 66, and by a switch 90 controlled by the air metering device mentioned above.

The air-metering device consists of a positive displacement air motor 91 of vane or other suitable type through which the starting air passes from a reservoir 92 on the way to the valve 86 and so to the engine. On the inlet and delivery sides respectively of the air motor 91, are two automatic pressure reducing and controlling valves 93, 94, so designed as to keep the inlet and delivery pressures of the motor approximately constant, the mean pressure required here being substantially below that normally obtaining in the starting air reservoir 92. A shut-off valve 95 and a throttle valve 96 are also provided. The air motor 91 is arranged to drive a flange 97 on a shaft 158 through gears 151. The flange 97 drives through an electromagnetic clutch 98 a second flange which is urged by a spring to return to a datum position whenever the clutch is disengaged. The latter flange carries a projection 99, arranged to engage a pivoted contact arm 100, after the clutch 98 has turned through a certain angle, and move it against the action of a spring 101. The arm 100 carries at one end one contact of a normally closed switch 90 for operating the air-valve and at the other end one contact of a normally open switch 14 for operating the fuel valve, and one contact of a normally open switch 103, for energising a holding coil 104. The second contact of the switch 90 is supported by a spring 102, which is displaced by the force of the spring 101, and the adjustment of the contacts is such that when the arm 100 is moved (by the projection 99 of clutch 98) the switch 103 makes before the switch 74 makes or the switch 90 breaks.

The electromagnetic clutch is connected in parallel with the air-valve-controlling solenoid 87 and in series with the switch 90 and the cam switch 88. Hence if and when the cam switch is closed (and the selector switch placed in the starting position) the air valve will be opened and the clutch engaged so that as the air passes into the cylinder the pin 99 will move towards the contact arm 100. After a predetermined movement, corresponding to a predetermined metered charge of air, the arm 100 is swung in a clockwise direction (as viewed in the drawing). This first closes the switch 103, which is connected in series with the holding coil 104 and the fuel cam switches 66, and thereby holds the arm 100 in its clockwise position until the circuit is broken by the fuel cam switches 66. Next the switch 90 is opened, closing the air valve and releasing the electromagnetic clutch which flies back to its initial position under the action of the before-mentioned spring. Finally the arm closes the switch 74, which is in series with the fuel valve-controlling solenoid and fuel cam switches 66, thereby opening the fuel valve to start the admission of fuel which continues, under the control of the

pressure limiting device, until the fuel cam switches break circuit, closing the fuel valve and releasing the contact arm 100 from its holding coil.

For use in the boosting cycle the air valve 86 can also be connected through a stop valve 108, an equalising chamber 107, and a reducing valve 106 to a boost air reservoir 105. Stop valves 108 and 95 are interconnected, so that when one is open the other is closed. When boosting, the air-valve-controlling solenoid 87 is connected, by a switch 110, in series with a single boosting cam-switch 109 (similar in construction to the cam-switch 66), the selector switch 73 in the fuel and air valve circuits being simultaneously moved to the normal running position, thus cutting out the cam-switch 88 and the air meter switches 90 and 14. The boosting cam-switch 109 times the air valve 86 to open and close late on the compression stroke of the engine.

Two separate rows of exhaust ports, 111 and 112, are provided towards the outer end of the engine cylinder 60, and these are uncovered successively by the engine piston, 113, on its outward stroke. The inner ports 111, which are the first to be uncovered, communicate through non-return valves 114, with an ante-chamber 115 of an exhaust gas turbine 116, which exhausts to atmosphere by a pipe 117. The second row of exhaust ports 112 communicate with the atmosphere through pipes 118 and 119. The piston 113 is connected to a crank-axle 120 by a connecting rod 121.

An air pump 122, driven from the crank-axle 120 through a connecting rod 123, normally delivers scavenging air through an air trunk 124, non-return valves 125 and scavenging ports 126 to the engine cylinder 60. Alternatively the air pump 122 can deliver through a pipe 132 and an inter-cooler 127 to a second stage air compressor 128, which is driven by gearing 129, from the crank-axle 120, and which delivers air through an after-cooler 159 to the starting and boost air reservoirs 92 and 105. This change-over is effected by closing a valve 130 in the air trunk 124 and opening a valve 131 in the pipe 132. Alternatively the scavenging pump can discharge to atmosphere through a valve 151.

The exhaust turbine 116 drives a blower 133 which delivers compressed air to a manifold 134, whence the air may be admitted to the engine cylinder 60 through a timed supercharging air valve 135, and supercharging ports 136, which succeed the scavenging ports on the inward stroke of the piston. The supercharging air valve 135 may be hydraulically operated in a similar manner to the valve 86, connection to the hydraulic accumulator 63 or tank 64 being made through a solenoid-operated distribution valve 137, controlled by an electrical cam-switch 138, on the camshaft 89, in series with an isolating switch 139. The latter remains open when starting and boosting. In normal running the supercharging air valve 135 is timed by the cam switch 138 to open as the scavenging ports 126 are covered by the incoming engine piston 113. A valve 140 permits the blower 133 alternatively to supply scavenging air to the scavenging ports 126 in place of the scavenging pump.

To control the compression pressure under conditions of low speed and heavy supercharge means are provided for injecting water into the engine cylinder. For this purpose a chamber 141 is put into communication with the engine cylinder 60 through a pipe 142 and a sampling valve

143 for a short period immediately on the completion of the supercharge. A water pump 144 operated by pressure from the engine cylinder 60 in conjunction with a spring, delivers water through a metering orifice 145 and a non-return valve 146 to a nozzle 147 which injects a spray of water into the engine cylinder 60 during the compression stroke. The metering orifice 145 is controlled by the pressure in the chamber 141 which will vary according to the degree of supercharge. A spill valve 148 cuts off the supply of water to the nozzle 147 at the end of the compression stroke of the engine. The valves 143 and 148 are operated respectively by engine-driven cams 149 and 150.

Figure 6 shows an arrangement by which the pressure in the chamber 141 is also employed to indicate and to help control automatically the latest allowable point of cut-off, i. e. the closure 20 of valve 61, according to the degree of supercharge and to the speed in normal running.

Moreover provision is made, by what may be termed a picking-up cycle, to supersede the output of the blower when the corresponding permissible cut-off is insufficient. This is achieved by connecting the manifold 134 to the boost reservoir 105, through a reducing valve 152 and an accelerating air valve 153, a non-return valve 154 in the blower discharge pipe 155 preventing a reversal of flow through the blower. It is proposed to link the valve 153 to the cut-off controls in such a way that when in normal running the cut-off is increased manually beyond the point corresponding to the pressure in the chamber 141, the valve 153 will open, admitting sufficient air to correct the fuel/air ratio and thus providing the volume of exhaust gas necessary to accelerate the turbo-blower rapidly to meet the new conditions.

Gas fuel is supplied to the valve 61 under pressure from a gas reservoir, or bottle, 156. The hydraulic accumulator 63 is kept charged by an hydraulic pump 161, driven by an electric motor 162, automatically regulated according to the level of the fluid in the accumulator.

The sequence of operations while starting and accelerating to full speed may be described as follows. Considering the engine and train to be initially at rest, and the piston 113 to be just beyond its inner dead centre, gas fuel is supplied to the valve 61 (which is closed) under pressure from the gas reservoir 156 by opening the stop valve 163. The valves 95 and 96 are then opened and the switch 73 set to start. The consequent flow of electric current through the switch 90 and cam-switch 88 energises the clutch 98 (causing it to grip the flange 97) and the solenoid of the valve 87, which opens. Thereupon the valve 86 opens and air flows into the cylinder 60 through the air motor 91, which revolves and turns the flanges 97 and 98 through the gears 157. The air pressures before and after the air motor 91 being held approximately constant by the regulating valves 93 and 94, a certain number of revolutions of the motor 91 will represent a certain weight of air. When the required air charge has been delivered, the stop 99 carried on the clutch flange 98 touches the contact arm 100 and revolves it on its pivot, causing the switch 103 to make, thus energising the electromagnet 104 which attracts and holds the arm 100 whereupon the switch 90 breaks and the switch 74 makes, in that order. Current now ceases to flow in the solenoid of the valve 87, causing the valve 86 to close, and in the coils of the clutch flange 98,

which, being released from the flange 97, immediately returns to its original position (under the action of the before-mentioned spring) where it remains until the beginning of the next cycle. The closing of the switch 74 allows electric current to flow through the solenoid 65 and cam-switches 160 and 66. The valve 62 therefore opens, causing the fuel valve 61 to open and to inject gas fuel into the cold compressed air in the cylinder 60, whereupon the fuel is ignited from the beginning of injection by the ignition apparatus incorporated in the valve 61, as described in British patent specification No. 527,612.

The piston 113 is now in motion, but at low speeds the rate of addition of heat will be such as to cause the cylinder pressure to rise despite the displacement of the piston. At a predetermined cylinder pressure (governed by the pressure in the air vessel 17) the pressure regulator piston 75 will begin to move outwards, reducing the lift of the valve 61 (through the linkage already described) and so limiting the rate of injection of fuel that a given maximum cylinder pressure is not exceeded. Injection of burning fuel continues until the point of cut-off is reached, which is governed by the setting of the brushes about the cam-switches 66 and 160. Expansion then takes place and the piston moves forward until the exhaust ports 111 are uncovered, whereupon the majority of the cylinder contents escapes in a surge to the turbine ante-chamber 115, reflux being prevented by the valves 114. From the ante-chamber 115, the exhaust gases pass to atmosphere through the turbine 16, accelerating it in their passage. The remainder of the cylinder contents escapes directly to atmosphere as the piston covers the ports 112. In the meantime the scavenge pump 122 has completed a stroke and has delivered air under pressure to the air trunk 124. This air now enters the cylinder 60 through the non-return valves 125, driving out what remains of the exhaust gas and supplying a fresh charge. Compression then takes place and the next cycle begins. The maximum pressures reached during the cycle may be widely varied by adjusting the pressure in the air vessel 17. For instance the first cycle on starting may be limited to a low maximum pressure and subsequent cycles may have progressively higher maximum pressures; the pressure in vessel 17 being steadily raised from a low to a high value over the starting period. The indicator diagram of Figure 2 for the starting cycle is seen to bear some resemblance to that obtained from a high pressure steam engine working at late cut-off. The quantity of starting air required to produce a given mean effective pressure by this method is much less than would be required were the air not heated in the engine cylinder.

As soon as the engine and train have attained a moderate speed—say 5 to 10 miles per hour—the switch 13 is changed over to “run,” the switch 110 is set to “boost,” the valve 95 is shut and the valve 108 is opened. The engine now functions on the more economical “boost” cycle typified in Figure 3, the valve 86 being timed by the cam-switch 109 to open for a short period late on the compression stroke. As will be clear from Figure 3 the low temperature and high pressure of the air so admitted to the engine cylinder permits a heavy supercharge to be carried without exceeding normal maximum pressures, and allows of a considerable higher fuel/air ratio within normal limits of temperature than is practicable with conventional methods of super-

charging. At low speeds too much air will at first enter the cylinder when the valve 86 is opened. The excess is displaced by the piston and is accommodated in the chamber 107 with but slight rise in pressure. At a higher speed the desired quantity will have entered as the valve 86 closes. Preferably boosting should cease at this higher speed. Above this speed the cylinder pressure as the valve 86 closes would become progressively lower and the degree of supercharge would tend to decrease in inverse proportion to the speed.

Boosting may, however, be continued for so long as sufficient air pressure remains in the boost reservoir 105; the final speed depending on the weight of the train and on the grade.

To change over from boosting to normal running, the switch 110 is opened and the switch 139 is closed, causing the starting air valve 86 to remain closed and the supercharging air valve 135 to be brought into operation. Normal supercharging now takes place, the charge being supplied by the exhaust turbo-blower, 116, 133, through the supercharging air valve 135 and the ports 136; scavenge air being supplied normally by the scavenge pump 122. The degree of supercharge will now tend to vary inversely as the speed, owing to the tendency of the proportion of exhaust gas trapped in the turbine ante-chamber 115, by the reflux valves 114, to vary in this manner.

It may also be noted that, at speeds above those at which the pressure regulator 75 comes into action, for a given cut-off, the quantity of fuel injected and, therefore, the out-put of the engine, will vary inversely as the speed.

No water injection takes place during starting and boosting, nor at moderate and high speeds in normal running, because the pressure in the chamber 141 (which is put into communication with the engine cylinder 60 by the sampling valve 143 early on the compression stroke) is insufficient to open the water metering orifice 145 against the opposition of a spring load. In normal running if the speed should drop owing to a steep gradient, the degree of supercharge will steadily increase, as will the pressure in the chamber 141, until below a certain speed water injection will automatically begin and will vary in quantity with the degree of supercharge. The effect is to lower the compression pressure and temperature to such an extent as to permit very heavy supercharges and relatively high fuel/air ratios to be employed within normal limits of pressure and temperature. This cycle, which is illustrated by Figure 4, may continue indefinitely and down to the lowest speeds. The pressure in the vessel 141 may also be used to help regulate the maximum permissible cut-off according to the amount of supercharge and the speed as described below in connection with Figure 6.

If speed is deliberately reduced, as for a signal check, by shifting the cam-switch brush 70 or 72 so as to reduce or prevent the injection of fuel, the turbo-blower will slow down and the pressure in the chamber 141 will drop correspondingly. To re-accelerate without having recourse to boosting, the valve 153 may be linked to the fuel cut-off controls in such a way that if they are set to inject more fuel than that corresponding to the pressure in the chamber 141, the valve 153 will open. By this means the fuel/air ratio will be corrected and the turbo-blower accelerated rapidly to meet the new conditions. Such an arrangement is shown diagrammatically in Figure 6 in which movement of the control lever 200,

11

which moves over a quadrant 201 to vary the cut-off by shifting the brushes 70 and 72, is limited by an adjustable stop. The latter is formed by the tappet 202 of a pilot valve 203 serving, when opened, to admit air from the reservoir 92 to operate the pressure-operated valve 153. Thus if the control lever 200 is up against the stop 202 the valve 153 will be opened.

The position of this stop is determined in accordance with the degree of supercharge, as indicated by the pressure in the chamber 141, and, at moderate and higher speeds, in accordance with speed. Thus the pilot valve 203 is carried by a sliding rod 204 urged to the right (as seen in Figure 6) by a spring 205 and controlled by a floating lever 206. One end of the latter is connected to a piston rod of a piston 210 in a small auxiliary cylinder 211 connected to the chamber 141 through a valve 212 coupled to the valve 154 to open and close with it.

Hence if the valve 153 is opened to supply super-charging air from the reservoir the non-return valve 154 and with it the valve 212 will close and remain closed until the blower has speeded up enough to re-open the non-return valve. Only then will the valve 212 re-open and allow the auxiliary piston 211 to take up an altered position corresponding to the altered degree of supercharge.

The other end of the floating lever is connected to a governor 220 provided with a stop 221 so that below a predetermined speed it does not affect the position of the floating lever.

To bring the engine and train to a standstill, fuel injection is stopped by opening the switch 73, the valve 131 is opened and the valve 130 is closed. The scavenge pump 122 and the second-stage compressor 128 then act as a regenerative brake utilising the unwanted kinetic energy of the train to re-charge the air reservoirs 92 and 105 in readiness for the next start.

As previously mentioned, the reservoirs 105 and 92 can also be replenished when an excess of power is available. For instance this could be done by opening the valves 140 and 131 and closing the valve 130. Scavenge air would then be supplied by the turbo-blower 133, while the scavenge pump 122 and second-stage compressor 128 would charge the reservoirs 105 or 92 or both.

What I claim as my invention and desire to secure by Letters Patent is:

1. An internal combustion engine having starting means including means, capable of operating when the engine is stationary, for introducing a charge of cold precompressed starting air into a cylinder when its piston is stationary and near the beginning of the working stroke, means for thereafter introducing fuel into the said completed charge of cold starting air in the same cylinder, and means for igniting the fuel as it enters the said cylinder whereby it is burned in the said charge of cold starting air in the said cylinder during the same working stroke.

2. An internal combustion engine as claimed in claim 1 including a metering device, to control the admission of air, which automatically cuts off the supply when a predetermined quantity has passed irrespective of the engine speed.

3. An internal combustion engine as claimed in claim 2 including a metering device which not only controls the admission of starting air but also controls the admission of fuel.

4. An internal combustion engine as claimed in claim 3 in which the metering device includes a positive displacement air-driven motor having

12

reducing valves to maintain substantially constant pressures on both its inlet and delivery sides, and an air engine admission valve arranged to be closed by a predetermined rotation of the motor.

5. An internal combustion engine as claimed in claim 4 in which the metering device operates through servo mechanism.

6. In an internal combustion engine, means for metering the supply of precompressed starting air to the cylinder and for thereafter operating the fuel valve, consisting of a positive displacement air motor in series with a constant pressure air supply to the cylinder, a movable part arranged to be driven by the air motor through a distance representing to scale the quantity of air which it is required to deliver to the engine at one time, and after moving the said distance to interfere with the contacts of a servo mechanism in such a way as firstly to close the starting-air valve, secondly to open the fuel injection valve, in that order, and finally to re-set itself in readiness for a subsequent cycle.

7. An internal combustion engine having means for automatically controlling the rate of admission of fuel in accordance with the pressure in the engine cylinder so as to prevent the latter rising above a predetermined figure.

8. In an internal combustion engine means for starting-up on load including means for introducing a measured charge of starting air to successive cylinders, means for thereafter burning fuel in each completed charge of air and means for preventing excessive cylinder pressure from arising however slowly the engine may move.

9. An internal combustion engine as claimed in claim 7 in which the means for controlling the pressure comprises an auxiliary cylinder containing a piston subject to engine cylinder pressure tending to move it against a resilient force away from a stop, the fuel injection valve being so controlled by the piston that its opening is reduced if the piston is displaced from its stop.

10. An internal combustion engine having means for introducing a supercharge of cold precompressed air into the cylinder late in the compression stroke in addition to the normally aspirated charge of primary air already being compressed by the piston to give a high total air charge without excessive air pressure or temperature, thereafter injecting fuel into the cylinder.

11. An internal combustion engine as claimed in claim 10 having a starting air valve for admitting air when starting, in which this valve is used for the admission of the precompressed delayed supercharge when running.

12. An internal combustion engine as claimed in claim 10 in which the air is supplied from a high-pressure reservoir through a reducing valve and an equalising chamber so that, if at low speeds the cylinder pressure exceeds the pressure setting of the reducing valve late in the compression stroke, air can be returned from the cylinder to the equalising chamber to prevent overcharging of the cylinder.

13. An internal combustion engine as claimed in claim 7 in which the admission of fuel is also controlled in accordance with crankshaft angle subject to manual adjustment so that the position of cut-off can be advanced or retarded.

14. An internal combustion engine including means for automatically setting the point of fuel cut-off according to the quantity of air present in the engine cylinder, comprising a chamber, a

timed sampling valve serving to put the chamber into communication with the engine cylinder for a period during the compression stroke and means for employing the pressure in this chamber to control the position of the fuel cut-off regulator.
